UNITED STATES PATENT OFFICE.

LEON K. McBREEN, OF SEATTLE, WASHINGTON.

DESIGN FOR AN AUTOMATIC WATER-GAGE CASING.

51,020.

Specification for Design.

Patented July 10, 1917.

Application filed September 2, 1916. Serial No. 118,275. Term of patent 3½ years.

To all whom it may concern:

Be it known that I, LEON K. McBREEN, a citizen of the United States, and a resident of Seattle, in the county of King and State of Washington, have invented a new, original, and ornamental Design for an Automatic Water-Gage Casing, of which the following is a specification, reference being

had to accompanying drawing, forming a part thereof.

The figure is a front elevation of an automatic water gage showing my new design.

I claim:

The design for an automatic water gage casing as shown.

LEON K. McBREEN.
